US00D794613S

(12) **United States Design Patent** (10) **Patent No.:** **US D794,613 S**
(45) **Date of Patent:** **** Aug. 15, 2017**

(54) **EARBUD HEADPHONE ADAPTER**

(71) Applicant: **Inca Street Sound, LLC**, Denver, CO (US)

(72) Inventor: **Thomas G. Hayden**, Denver, CO (US)

(73) Assignee: **Inca Street Sound, LLC**, Denver, CO (US)

(**) Term: **15 Years**

(21) Appl. No.: **29/557,189**

(22) Filed: **Mar. 7, 2016**

Related U.S. Application Data

(63) Continuation-in-part of application No. 15/062,088, filed on Mar. 5, 2016.

(51) **LOC (10) Cl.** **14-01**

(52) **U.S. Cl.**

USPC **D14/223**

(58) **Field of Classification Search**

USPC D14/223, 205; D24/174; 181/129, 130, 181/135; 379/430, 431, 433.01; 381/328, 380, 381

CPC H04R 1/10; H04R 1/105; H04R 25/00; H04R 25/02; H04R 25/652; H04R 1/1016; H04R 1/1066

See application file for complete search history.

(57) **CLAIM**

The ornamental design for earbud headphone adapter, as shown and described.

DESCRIPTION

FIG. 1 is a front perspective view of earbud headphone adapter;

FIG. 2 is a back view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken lines depict environment that forms no part of the claimed design.
